UNITED STATES PATENT OFFICE.

CHARLES FRED DORRANCE, OF PORTLAND, OREGON.

DESIGN FOR A BADGE.

SPECIFICATION forming part of Design No. 23,788, dated November 13, 1894.

Application filed August 9, 1894. Serial No. 519,882. Term of patent 7 years.

To all whom it may concern:

Be it known that I, CHARLES FRED DORRANCE, a citizen of the United States of America, residing at Portland, in the county of Multnomah and State of Oregon, have invented and produced a new and original Design for Badges; and I do hereby declare the following to be a full, clear, and exact description of the same, reference being had to the accompanying drawing, forming a part thereof.

The drawing is a face view of a badge illustrating my new design.

The badge comprises for its leading features a monogram made up of the characters or letters "P A C," the stem and lower part of the loop of the "P" passing through the upper loop of the "A" and below the cross-bar of the same so that the stem of the "P" divides the "A" to form two "A's". The "C" is positioned between the side members of the "A" and below the stem of the letter "P," the upper part

of the said letter "C" crossing the scroll which extends from one of the side members of the "A". From the side members of the central character or letter projector extend wings *a. a.* 25

The accompanying drawing fully illustrates the arrangement and character of my design for badges and similar articles of jewelry for personal wear.

Having thus described my design, what I claim as new, and desire to secure by Letters Patent, is—

The design for a badge or similar article of jewelry for personal wear as shown in the accompanying drawing. 35

In testimony whereof I affix my signature in presence of two witnesses.

CHARLES FRED DORRANCE.
